CRUMBER ADJUSTMENT FOR ENDLESS-
TYPE TRENCH DIGGING MACHINESGeorge A. Vaughn, Newton, Iowa, assignor to The
Parsons Company, Newton, Iowa, a corporation

Application May 27, 1948, Serial No. 29,622

2 Claims. (Cl. 37—90)

1

This invention pertains to the art of excavating machines, and involves improvements in what are known as trenching or ditch digging machines of the ladder type.

The type of machine just referred to utilizes an enclosed boom and multiple buckets carried by endless chains traveling along the boom to dig the trench or ditch in a continuous manner to a predetermined depth, as the machine moves forwardly.

My present invention resides in providing a boom of the nature above mentioned which has a floating mounting on the frame of the machine, may be pulled up for inaction of the digging means, or lowered for action thereof, and which carries at its lower end a crumber for leveling and smoothing the ditch bottom as it is excavated. The crumber is designed to carry a portion of the weight of the boom and digging devices, and has associated novel means for adjusting same relative to the boom.

A full understanding of my invention will be had upon reference to the following detailed description and to the accompanying drawings, and in the latter:

Figure 1 is a side elevation generally showing a machine embodying the essential features of my invention.

Figure 2 is a fragmentary top plan view showing more clearly the adjustable crumber means carried by the lower end of the digging boom, an upper cross member of the boom frame omitted.

Figure 3 is a top plan view of the instrumentalities for adjustably connecting the boom sections.

Figure 4 is a longitudinal vertical sectional view taken through adjacent ends of the boom sections showing the adjusting and yielding control parts.

Figure 5 is a fragmentary vertical sectional view of the lower end of the boom and wheel and crumber parts carried thereby, certain parts broken away.

Figure 6 is a cross section on the line 6—6 of Figure 1, showing the rollers on the upper boom section for lateral adjustment of the boom.

Referring to my drawings it is notable that an excavating or trenching machine of the type of my invention generally includes a body structure having the frame 1 mounted upon crawler units 2 or like portable supporting means, the frame or chassis 1 carrying upwardly extending side frame members 3 which side frame members are curved at their upper edges so that the rear and upper edge portions of said frame members may

2

constitute tracks designated 4. The machine will be propelled by a suitable engine such as shown in dotted lines at 5 in Figure 1. The engine 5 is connected to drive certain parts of the excavating or digging devices to be later described.

On the superstructure of my machine body are mounted a pair of arms 6 which are adapted to pivot upwardly and downwardly in relation to the position in which they are shown in Figure 1. These arms are pivotally connected at their upper ends to a boom generally designated at A and consisting of an upper rectangular tubular section 7 and a lower section 8. The lower section 8 telescopes in the hollow portion of the upper section 7. In this manner the boom is extensible and suitable bolts 9 and other parts may be employed by which to connect the boom sections 7 and 8 in adjustable and yieldable relation.

To the above end the bolts 9 are pivoted at corresponding ends to opposite ends of a clevis bar 10 which passes transversely through a selected pair of several sets of transverse registering slots 11 in the boom section 7. Bolts 9 are adjustably connected by nuts 12 to angle lugs 13 on the boom section 7. On the lower edge of the bar 10 is a spring seat 14 for one end of a spring 15, the other end of said spring bearing against a spring seat 16 consisting of a plate welded in place in the upper hollow portion of the boom section 8.

The foregoing structure permits of lengthening and shortening the boom within certain limits, by adjusting the nuts 12 or the position of the bar 10 in the sets of slots 11, and thereby enables increasing and decreasing digging depth operation of the excavating or digging instrumentalities which are carried by the boom. The spring 15 compensates for or absorbs shock when the buckets 17 of the excavating means encounter obstacles, or stones are caught between the bucket chain 18 and lower idler wheel 26.

A pivot shaft 20 forms the pivot connection between the upper end of the boom and the spaced arms 6 previously referred to. For the rocking of the arms 6 to raise and lower the boom A there may be provided any conventional means such as used in the art. I illustrate diagrammatically certain cable operating means designated 21 (see Figure 1) which means is connected to the hood 22 attached to the upper ends of the arms 6 adjacent to the part 7. Winding of the cables 21 on suitable drums 23 will elevate the boom A and unwinding action of the cables will permit the boom to move downwardly relative to

the side members 3 of the frame of the machine. Sprockets 24 are mounted on the shaft 26 and the endless sprocket chains 18, before mentioned, pass around said sprockets at their upper ends, the lower ends of the chains 18 passing around the spaced rims 25 of a lower chain wheel 26 disposed adjacent to the lower end of the boom. The sprocket chains 18 travel on the rims 25 and are prevented from lateral displacement by edge portions 27 of said wheel 26 after well known practice.

The chains or carrier means 18 carry the digging buckets 17 which may be equipped with teeth and which perform the digging operation in the ditch which is made by the operation of the machine, incident to being carried downwards and upwards by the chains 18 after well known practice.

The wheel 26 is made up of spaced vertical side members connected at the axis portions by a bearing hub 28 fitting into a bearing sleeve 30 on the lower end of the boom section 8 so the hub 28 may revolve in the axis member 30. The hub 28 is hollow and extending therethrough is a pivot shaft 31 on which a crumber frame 32 is mounted.

This crumber frame 32 is of approximately rectangular form. Downwardly extending and tapering side plates 33 on opposite sides of the frame 32 are pivotally connected to the boom section 8 by receiving at their lower ends the pivot shaft 31.

The crumber frame 32 is thus adapted to pivot on the lower end of the boom section.

The crumber frame 32 supports at its rear end a relatively vertical arm 34 which also in turn supports at its lower end the crumber shoe 35 which is of a flat horizontal blade-like structure and adapted to operate on the lower or bottom surface of the trench being excavated during the forward movement of the machine, incident to the rotation of the wheel 26 as the buckets 17 are carried by the chains 18 around the wheel. Braces 36 connect the upper end of the arm 34 with the middle part of the frame 32.

Mounted on the lower section 8 of the boom A is a hydraulic unit or ram designated 37 and the piston rod of this ram is connected pivotally at 38 with the forward end of the crumber frame 32. Suitable hydraulic or fluid pressure supply pipes 39 lead to the upper and lower ends of the cylinder of the unit 37 to supply and exhaust pressure fluid at opposite sides of the piston in said unit, not shown, whereby the piston rod of the unit may push upwardly or pull downwardly on the front end of the crumber frame 32.

Accurate grading as respects the bottom of the trench formed by my excavating machine, is accomplished by rotating the crumber frame on the pivotal axis 31 by operation of the hydraulic unit or pressurized unit 37 thereby to raise or lower the crumber shoe 35, this permitting the buckets 17 to dig slightly deeper or shallower as desired.

When the boom A is raised or lowered for adjusting the digging depth, such operation is performed incident to the action of the movement of the crumber frame and crumber shoe because in the usual operation of the machine, the boom A has a floating mounting on the pivotal shaft supporting means 20 and the weight of the boom is thus carried partly by said shaft 20 and partly by the engagement of the crumber shoe at the bottom of the ditch being excavated by the buckets 17. In the above manner the digging depth of the buckets 17 is really controlled by the ad-

justment of the crumber unit including the parts 32, 34 and 35.

A sight rod 40 is mounted on a vertical standard 41 on the crumber frame 32 and is normally pivoted and balanced to remain in a horizontal position, in respect to two or more sight rods with horizontal bars which are set in the ground at a proper height above the grade stakes set by a surveyor for the proper grade and location of the trench. The operator determines the digging depth of the digging buckets by sighting along the sight rod 40 above mentioned.

When the boom A is hoisted to raise the bucket excavating means above the ground for placing the same out of use, rollers 42 on frame 43 attached to the upper section 7 of the boom will engage with the curved tracks 4 on the side frame parts of the machine body so as to facilitate the raising of the boom and the forward travel of the latter in relation to the frame of the machine as the excavating devices are caused to be disengaged from the ground and rendered inoperative. It is also apparent that the rollers also limit the extent of downward pivotal movement of the outer end of the boom, depending on the position of the pivot 20, the rollers being adapted to engage the tracks when the boom has reached a predetermined position.

The pressure unit 37 may be used for adjusting the crumber shoe 35 under all conditions of use of the machine including a condition wherein the boom A is raised necessitating pushup action on the member 38 to levelize the shoe 35 or when the boom A is lowered, necessitating a pull-down action on the part 38 for the same purpose.

The frame 43, as seen in Figures 1, 2, and 6 supports the boom A and the latter may be adjusted on the frame toward either side of the latter by sliding movement. The upper cross frame bar 44 seen in Figure 6 is omitted in Figure 2 to show the lower cross frame bars 44a that pass under the boom. The lateral shifting of the boom A on the frame enables the positioning of the boom and digging devices at different positions transversely of the machine. The boom A is fixed in its position on the frame 43 by clamping bolts 48. Rollers 49 on the boom section 7 support the boom A on the frame 43 when stationary and moving sidewise.

Guide arms 45 project downwards from the frame 43 adjacent the rollers 42 and extend on the inner sides of the main frame sides 3 to guide the up and down shifting movements of the boom frame 43 with its boom A, preventing lateral displacement of the latter. Upper and lower brackets 46 on boom section 7 have rollers 47 to engage and guide the upper and lower laps of the chains 18. The chains 18 are kept under tension by the spring 15 action maintaining the boom section 8 under compression. The tension on the chains 18 is sufficient to pull the crumber attachment on the lower boom section.

In order to carry off the materials dug by the bucket excavating means 17, a conventional conveyor B is provided, the same being supported on the frame of the machine and beneath the upper end of the digging chains. The materials deposited onto the conveyor B is thus moved to one side or the other of the machine. The conveyor B may be driven in the usual manner so as to effect the movement of the materials as desired, the same comprising well known construction and forming no part of the present invention.

Having thus described my invention, what I claim as new and desire to secure by Letters Patent of the United States, is:

1. In a trench digging machine, in combination, a body comprising a portable traction base, a boom, mounting means between the boom and body supporting the boom from one end in a floating manner on the body, carrier means comprising endless members movable longitudinally of the boom, a wheel on the boom at its outer end about which the endless carriers pass, digging instrumentalities on said carrier means to move therewith, a crumber unit including a horizontal blade-like shoe movable on the bottom of a ditch dug by the digging instrumentalities, said shoe being mounted on a rigid frame pivotally connected to the boom for supporting same at its outer end, and a power unit on the boom connected with the rigid frame of the crumber unit to shift the said unit around the pivotal mounting therefor.

2. In a trench digging machine, in combination, a body comprising a portable traction base, a floating boom, a pivotal connection between one end of the boom and said body enabling the boom to swing in a downward direction from the body, an endless carrier on said boom for travel longitudinally thereof, digging buckets connected to said carrier, and a crumber unit comprising a rigid frame consisting of a horizontal member, an arm extending downwardly at the rear of said member, a flat horizontal blade on said arm engageable with the earth at

the bottom of a trench being excavated, a second arm at the other end of said member, said second arm being pivotally connected to the boom at its free rear end to support the buckets during their digging operation, and a power device connected to the boom and to the horizontal member for adjusting the shoe on the arm at the rear thereof, around the pivotal connection of the second arm and the boom.
